UNITED STATES PATENT OFFICE.

RAYMOND W. DULL, OF LA GRANGE, ILLINOIS, ASSIGNOR TO LINK BELT COMPANY,
OF CHICAGO, ILLINOIS, A CORPORATION OF ILLINOIS.

LOCKING LINK FOR CHAIN BELTS.

Application filed September 2, 1920. Serial No. 407,818.

To all whom it may concern:

Be it known that I, RAYMOND W. DULL, a citizen of the United States, residing at La Grange, in the county of Cook and State 5 of Illinois, have invented a certain new and useful Improvement in Locking Links for Chain Belts, of which the following is a specification.

My invention relates to improvements in 10 link belt chains and has amongst its objects to provide links for such chains which shall have vertical instead of horizontal side bars.

Other objects and advantages will appear from the description. The invention is illustrated in one form in the accompanying 15 drawings wherein:

Figure 1 is a plan view of a channel bar from which the links are to be made;

Figure 2 is a cross section on the line 2—2 20 of Figure 1;

Figure 3 is a plan view of a link blank with the scoring lines;

Figure 4 is a sectional view of the finished link;

Figure 5 is a cross section on the line 25 5—5 of Figure 4;

Figure 6 is a sectional view of two links in the process of being interlocked;

Figure 7 is a similar view of a second position;

Figure 8 is a side elevation of three links in interlocking relation.

Figure 9 is plan view of the finished link.

Like parts are indicated by the same letter in all the figures.

The channel bar is composed of the flat member A, and the side members A'A'. Without referring to the process by which the operation is carried on, it may be well 40 to say that of course, the blanks for the links could be made from such channel bar stock or from flat stock turned up at the edges to form the channel and it is a matter of difference when such edges are 45 turned up to form such channel.

As soon as they have been turned up, the link blank will be scored as indicated by the score lines B B in the corner of the channel and the transverse score line C 50 which connects them. This will facilitate the punching out of the hook and the cross bar and when such punching out takes place, the link will have a cross bar D, the hook E and the vertical side bars F F. The

mouth G of the hook E is narrower than the 55 width of the side bar F which will effectively prevent all relative lateral motion of any pair of links in any direction after the same have been interlocked. Because of this fact, the links will have to be disengaged in reverse of the operation by which they are interlocked if they are to be disassembled.

The proportions of the hook E and the 60 pintle or cross bar D are such that in the process of slipping the cross bar into the tubular interior of the hook there is a snug fit so that normally a degree of pressure is required to force the cross bar onto the hook and to remove it therefrom. This is particularly illustrated in Figures 6 and 7.

By having vertical side bars, this fit may be very snug and close because pressure can be applied to such vertical side bars to engage or disengage the links without fear of 70 such distortion as might easily occur were the side bars flat as would be the case if the links were made from flat stock and not from channel bar stock.

As soon as the side bars are extended in 80 a vertical direction, the scoring which is intended to make easy the punching out of the hook and cross bar, may be made by direct lines, the side lines extending up to the point where the bend begins, for since 85 the side bars are vertical, there will be little if any tendency for the metal to tear at this point during the process of forming the hook and cross bar. The side bars are 90 slightly spread toward their junction with the cross bar so as to widen the space between the side bars at this point to permit easy introduction to the hook.

It will be evident as above suggested 95 that the structure here shown could be greatly varied without departing from the spirit of my invention. What I have shown is to be merely taken as a suggestion of the general idea.

I claim:

1. A chain belt comprising a plurality of 100 separate links each having a cross bar at one end and a hook at the other with side bars slightly spread near the cross bar to give free access to the hook.

2. A chain belt comprising a plurality of 105 separate links each having a cross bar at one end and a hook at the other with side

- bars slightly spread near the cross bar to give free access to the hook, said side bars vertically extended.
3. A chain belt comprising a plurality of 5 separate links each having a cross bar at one end and an open hook at the other and adapted to be interlocked by the insertion of the cross bar through the hook opening, the parts formed so that pressure is required 10 to force the cross bar through the hook opening.
4. A chain belt comprising a plurality of 15 separate links each having side bars located in planes perpendicular to the plane of the link, a cross bar at one end, and a hook at the other, the side bars being bent upwardly at each end where they project in the hook and cross bar respectively.
5. A link for chain belts comprising vertical side bars upwardly curved at either end, 20
- the side bars being connected at one end by a hook portion in the form of a split cylinder, the opposite ends of the side links being connected by a concave surfaced pindle. 25
6. An integral chain link comprising vertical side bars connected at one end by a substantially tubular hook and at the other end by a concave surfaced pindle. 30
7. An integral chain link comprising vertical side bars connected at one end by a substantially tubular hook and at the other end by a concave surfaced pindle, the ends of the side bars being curved at each end in an arc substantially concentric with the hook 35 and the pindle respectively.

Signed at Chicago, county of Cook and State of Illinois, this 27th day of August, 1920.

RAYMOND W. DULL.
